UNITED STATES PATENT OFFICE.

HARRY B. DOHERTY, OF WILKES-BARRE, PENNSYLVANIA.

VALVE FOR INTERNAL-COMBUSTION ENGINES.

1,127,868.

Specification of Letters Patent.

Patented Feb. 9, 1915.

Application filed October 14, 1913. Serial No. 795,139.

To all whom it may concern:

Be it known that I, HARRY B. DOHERTY, a citizen of the United States, and a resident of Wilkes-Barre, Luzerne county, Pennsylvania, have invented certain Improvements 5 in Valves for Internal-Combustion Engines, of which the following is a specification.

My invention relates to internal combustion engines of the explosion type, in which 10 the inlet of the explosive mixture and the outlet of the products of combustion and waste gases is controlled by valves suitably driven from a moving part of the engine, and the object of my invention is to provide 15 an improved form of piston valve for controlling the inlet and exhaust to and from the cylinders.

The usual practice heretofore has been to 20 employ either puppet valves, which are raised by cams and lowered under the action of springs; separate and independent valves being employed to take care of the inlet and exhaust of each of the several cylinders, or sleeve valves surrounding the cylinder, and my improved valve is designed 25 to take the place of structures of these types.

My invention consists of an improved 30 form of piston valve disposed adjacent a pair of cylinders and designed to take care of the inlet and exhaust from the same, which valve is rotated for the purpose of bringing its ports into proper position with respect to the ports leading to the several cylinders and at the same time is reciprocated so that the port which has been employed 35 as the means through which exhaust may be discharged from a cylinder, becomes the means whereby a charge of gas is admitted to a cylinder. By employing a valve 40 with two cross or through passages, each passage having two ports, and arranging the same in proper relation with respect to the inlet and exhaust ports of a pair of cylinders, a single valve may be employed to 45 take care of both cylinders.

My improved valve is shown in its application to a four cylinder equipment, and it will be understood that the position of the passages is determined by the number of 50 cylinders of the equipment; the firing of the several cylinders taking place at different intervals.

These and other features of my invention

are more fully described hereinafter, reference being had to the accompanying drawings, in which:

Figure 1, is an elevation of a four cylinder engine equipment showing the position of the inlet and exhaust manifolds; Fig. 2, is an enlarged sectional elevation through the line 2-2, Fig. 1, showing one cylinder and its piston in dotted lines; Fig. 3, is a view partly in section looking at the end of the cylinders and showing the gearing for driving the valves; Fig. 4, is a sectional plan view, on the line 4-4, Fig. 2, illustrating one position of one valve and its passages; Fig. 5, is a similar sectional view, showing the valve with its passage in a different position; Figs. 6 and 7, are views similar to Figs. 4 and 5, showing other positions of the valve, and Fig. 8, is a view illustrating a development of one of the piston valve chambers.

In the drawings, 1 represents a casting having the usual water spaces 2, and bored to form cylinders 3 for the reception of pistons 4. This casting also includes a portion or shell 5 in which a valve chamber 6 is formed receiving a piston valve 7, which valve is arranged to be rotated and simultaneously reciprocated so as to bring its passages into proper registry with the inlet and exhaust ports between a pair of cylinders and the usual inlet and exhaust manifolds. The crank shaft is shown at 10, having the usual cranks 11, to which the connecting rods 12 of the several pistons are properly attached in the usual manner.

The piston valve 7 is a substantially solid cylindrical body, having a pair of passages 15 and 16 disposed at an angle with respect to each other, and the angle of this disposition will be determined by the number of 95 cylinders of the engine equipment with which my improved valve is employed. The valve has a stem 17 at its lower end, which passes through a pair of blocks 18 and 19, secured in the lower part of the shell 5 forming the valve chamber, which blocks are so shaped and so disposed with respect to each other that a cam path 20 is formed between the same whereby roller pins 21 carried by said valve stem may be actuated 100 or guided for the purpose of effecting lon-

itudinal movement of said piston valve which, in the present instance, is in a vertical direction, simultaneously with the rotation of the same; such rotative movement being effected by gearing as hereinafter described.

The valve stem is provided with an angular face or faces 22 and extends below the valve chamber; passing through a helical gear or pinion 25 suitably supported with respect to said valve stem and having anti-friction bearings. The pinion is thereby held in a fixed vertical position, so that rotative movement imparted thereto will be transmitted to the valve stem in driving engagement therewith but movable through the same, and thence to the piston valve. This movement is transmitted from a helical gear or pinion 26 on a shaft 27 suitably driven from the crank shaft by the gear wheels 28 and 29 on the shafts 10 and 27, and the pinions 28^a and 29^a carried by the shaft 30.

The blocks 18 and 19 are preferably of hardened steel and may be threaded into the lower part of the valve chamber, or they may be secured in place by screws or other fastening means passing through the wall of said chamber. In order to gain access to the roller pins 21 carried by the valve stem, I preferably provide an aperture 31 in the valve chamber, which is normally closed by suitable means, such as a plate 32. The piston valve is preferably marked on its upper end or head so as to indicate the position of the passages and facilitate its resetting or retiming.

The blocks 18 and 19 when properly positioned to form the desired cam path may be secured in such position by means of set screws passing through the walls of the valve casing, and it will be understood, of course, that both of said blocks 18 and 19 are adjustable with respect to each other in order to effect the reciprocation of the piston valve at the proper time. In addition, they are adjustable independently of each other so as to take up any wear and insure that the cam path is in proper position to effect the desired movement of the piston valve.

The main cylinders are provided with the usual ports or passages 35 and 36 for the inlet and exhaust of the explosive mixture and the products of combustion, respectively, which ports or passages may be curved and the end of the cylinder is tapped at 37 for the reception of the usual spark plug 38 whereby the charge may be ignited. The rotary piston valve 7 is so timed with relation to the movements of the pistons 4 that the passages and ports of said valve will be brought successively into proper position to admit of the passage of a charge of explosive mixture to the cylinders and to

provide for the exhaust of the products of combustion from said cylinders; the crank shaft being geared to the valve in the relation of four to one.

The vertically movable stem of the valve 70 may be employed as a pump to circulate oil between the bottom of the crank casing and oil carrying troughs 41 through which the cranks pass, and for this purpose, the lower end 42 of the stem of such piston valve may 75 fit within a chamber 43 near the bottom of the crank casing so that upon the upward stroke, oil will be drawn in by said piston from the crank casing, and by providing a check valve of suitable construction, a ball 45 for instance, the oil will be retained for discharge through a passage 46 to the troughs 41; the passage 46 being also provided with a check valve to prevent withdrawal of oil through the same when the 80 valve stem rises.

Figs. 4, 5, 6 and 7, showing sections through the cylinders and valve, illustrate the relation of the inlet and exhaust ports and passages to each other. Fig. 6, shows a plan view of the inlet and exhaust manifolds for the third and fourth cylinders, and Fig. 8, is a diagrammatic illustration of the ports of one of the valve cylinders.

By referring to Fig. 8, it will be seen that upon the first half revolution of the crank shaft, the valve 7 descends and rises again, and in this action fuel is admitted to cylinder A via passage 15; passage 16 being closed at both ends and fuel previously admitted to cylinder B is being compressed. Upon the second half revolution of the crank shaft with the valve 7 still rising; passage 15 is closed at both ends and cylinder A is under compression; passage 16 being closed at both ends, explosion is taking place in cylinder B. Upon the third half revolution of the crank shaft, the valve 7 rises and descends; passage 15 being closed at both ends, and explosion takes place in cylinder A, while passage 16 is open at both ends, permitting cylinder B to exhaust. Upon the fourth half revolution of the crank shaft, the valve 7 is still descending; passage 15 is open at both ends, permitting cylinder A to exhaust, while passage 16 is open at both ends, permitting inlet of fuel to cylinder B.

I claim:—

1. The combination, in an internal combustion engine, of a cylinder, a valve chamber paralleling the cylinder, a piston valve in said chamber having a single passage controlling both admission and exhaust of gases to said cylinder, and means for rotating and simultaneously reciprocating said piston valve.

2. The combination, in an internal combustion engine, of a pair of cylinders, a valve chamber paralleling said cylinders

and disposed for communication with both of the same, a piston valve in said chamber, said valve having a plurality of cross passages, each of said passages controlling both 5 admission and exhaust of gases to one of said cylinders, and means for rotating and simultaneously reciprocating said valve.

3. The combination, in an internal combustion engine, of a pair of cylinders, a 10 valve chamber common to both of said cylinders and paralleling the same, a reciprocating piston valve in said chamber having a plurality of cross passages, each of said 15 passages controlling both admission and exhaust of gases to one of said cylinders, and means for rotating said valve simultaneously with its reciprocations, said valve having two complete reciprocative movements for each rotative movement.

20 4. The combination, in an internal combustion engine, of a cylinder, a crank-shaft, a valve chamber adjacent to and paralleling the cylinder, a reciprocable piston valve in said chamber having a single passage controlling both admission and exhaust of gases 25 to said cylinder, gearing driven by the crank-shaft for rotating said valve, and means within said chamber for reciprocating said valve simultaneously with its rotative movement.

5. The combination, in an internal combustion engine, of a cylinder, a crank-shaft, a piston driving the same, a valve chamber paralleling the cylinder, a piston valve in 35 said chamber having a single through passage controlling the admission and exhaust of gases to and from said cylinder, gearing driven by the crank-shaft for rotating said valve, and a plurality of adjustable cams 40 within said chamber for effecting reciprocation of said valve during its rotative movements.

6. The combination of a plurality of cylinders, a valve chamber parallel to and 45 mounted between said cylinders and having ports or passages leading to both of said cylinders, a rotary piston valve mounted in said chamber and having a plurality of passages for registry with the ports or passages 50 leading to the cylinders, each passage of the piston valve serving alternately for inlet and exhaust, means for rotating said valve,

and means within the chamber for effecting simultaneous reciprocation of said valve.

7. The combination, in an internal combustion engine, of a cylinder, a valve chamber paralleling said cylinder, a piston valve in said chamber having a single passage controlling the admission and exhaust of gases to and from said cylinder, a plurality 55 of cams in said chamber for effecting reciprocation of said valve during its rotation, and means for adjustably securing said cams in place.

8. The combination, in an internal combustion engine, of a cylinder, a valve chamber paralleling the cylinder, a piston valve in said chamber having a single passage controlling the admission and exhaust of gases to and from said cylinder, means for 65 rotating said valve, a plurality of cams relatively fixed in said chamber for effecting reciprocation of said valve in both directions during its rotation, a stem carried by said valve and passing through the axis of 70 the same at right angles thereto, and a pair of roller pins carried by said stem for engagement with the cams whereby the valve may be reciprocated during its rotative movements.

80 9. The combination, in an internal combustion engine, of a cylinder, a valve chamber paralleling the cylinder, a piston valve in said chamber having a single passage controlling the admission and exhaust of 85 gases to and from said cylinder, means for rotating said valve, a plurality of cams in said chamber for effecting reciprocation of said valve in both directions during its rotation, a stem carried by said valve, a pair 90 of roller pins carried by said stem in engagement with the cams whereby the valve may be reciprocated during its rotative movements, said valve chamber having an opening for access to said pins, and a plate 95 covering said opening.

In testimony whereof, I have signed my name to this specification, in the presence of two subscribing witnesses.

HARRY B. DOHERTY.
